STAPLING MACHINE

Edward Krantz, Chicago, Ill., assignor to Fastener Corporation, Chicago, Ill., a corporation of Illinois

Application November 19, 1936, Serial No. 111,630

6 Claims.

(Cl. 1—3)

This invention has to do with stapling machines of the type in which the staples are driven into the paper or other material by means of a spring-actuated hammer.

5 The object of the invention is to provide an improved stapling machine of the character described which will operate efficiently in the manner intended, will give trouble-free service over a long period of time, requires no periodic adjustment, is quiet in its operation, can be opened up readily to permit the removal of any defective staples which may clog up the guideway for the driving blade, and can be manufactured at comparatively small cost.

10 15 While the foregoing statements are indicative in a general way of the nature of the invention, other objects and advantages will be evident upon a full understanding of the construction, arrangement and operation of the parts which 20 make up the machine.

A preferred embodiment of the invention—namely, a desk or office type of stapling machine—is presented herein for the purpose of exemplification, but it will of course be appreciated that the invention is capable of incorporation in other forms coming equally within the scope of the appended claims.

In the accompanying drawings:

Fig. 1 is a top view of a stapling machine constructed in accordance with the invention;

Fig. 2 is a side view of the machine;

Fig. 3 is a partially sectioned side view;

Fig. 4 is a horizontal section, taken on the line 4—4 of Fig. 3;

Fig. 5 is another horizontal section, taken on the line 5—5 of Fig. 3;

Fig. 6 is a vertical section, taken on the line 6—6 of Fig. 4;

Fig. 7 is a partially sectioned side view of the follower which is attached to the draw band;

Fig. 8 is a view which corresponds to Fig. 3 but shows the parts of the machine in the positions which they assume just as a staple is about to be driven;

Fig. 9 is a vertical section, taken on the line 9—9 of Fig. 2;

Fig. 10 is a perspective view, showing the lower end of the staple-driving blade and the front end of the staple-supporting bar;

Fig. 11 is a top view of the finger piece on the rear end of the draw band; and

Fig. 12 is a fragmentary side view of the machine at the location of the displaceable front guide plate, showing the latter swung forwardly

and downwardly to expose the driving blade and the guideway in which the blade moves.

Referring in more detail to the drawings, it will be observed that the machine includes a base 10 and a head 11. The base 10 is provided at its front end with a clinching die 12 and at its rear end with a bracket 13 of upwardly opening channel form in which the rear end of the head 11 is supported on a hinge pin 14. The lower part of the head 11 is in the form of an arm 15, while the upper part of the head is in the form of a casing 16. The arm 15 and casing 16 are connected with each other at their front ends by spaced side plates 17 and are separated from each other at their rear ends by a slot 18. The head 11 is provided at its front end with a vertically extending guideway 19 of rectangular cross section in which a plunger 20 or corresponding cross section is slidably mounted. This plunger carries a staple-driving blade 21 which is set back into a closely conforming cut-out portion in the front face of the plunger and is held in position by means of a rivet 22. The blade 21 moves up and down in a small slot 23 which is located in the head directly above and clinching die 12 on the base.

The arm 15, which forms the lower part of the hinged head 11, is composed of two nested channel members 24 and 25. The inner member 25 is spaced from the outer member 24 at its top 30 and at the upper portions of its sides (see Fig. 9), whereby to provide between the members a guideway 26 of inverted U-shape cross section for the reception of a large number of staples 27, which staples straddle and slide along the top of the inner member 25. The inner member 25 is closed off at its front end and is cut back, along with the overlying portion of the outer member 24 (see Fig. 10), to form the previously described slot 23 in which the staple-driving blade 21 moves. 35 The staples 27 are advanced along the guideway 26 by a sheet metal follower 28 (see Fig. 7) which is positioned in the guideway behind the rear-most staple. The follower 28 is provided with a button-like stud 29 which projects upwardly through a slot 30 in the top of the channel member 24 and is hooked through an aperture 31 in a finger piece 32 (see Fig. 11) attached to a draw band 33. The draw band is a strip of spring metal which is secured to a hub 34 and wound resiliently into a coil by means of the hub to apply constant tractive force to the follower. Under the action of the draw band 33 the finger piece 32 will move forwardly in the previously de- 50 55

scribed slot 18 in the head as the staples are used up.

The staple-driving plunger 20 is projected downwardly in the guideway 19 by the action of a coil spring 35. The spring 35 is positioned in the rear end of the casing 16 between the bottom of the casing and the rear end of a lever 36. The lever 36 is fulcrumed near its rear end on a pin 37 and is provided a short distance in front of the pin with a bumper block 38 for cushioning engagement with the bottom of the casing. The lever 36 is of channel form and is provided at its front end with two rounded ears 39 which extend forwardly from the two sides of the channel into undercut grooves 40 in the sides of the plunger. When the plunger is raised in its guideway the spring 35 will be compressed, with the result that when the plunger is released it will be driven downwardly by the spring with considerable force and speed and will deliver a hammer-like blow against the staple under the blade 21.

The plunger 20 is raised against the resistance of the spring 35 by means of a hand lever 41, which lever is pivotally mounted at its rear end on a pin 42 in the rear part of the casing 16. The lever 41 extends forwardly and upwardly through a narrow slot 43 in the center of the top of the casing and terminates in a round knob-like handle 44 which is located above the front end of the head 11. A roller 45, which is mounted on the under side of the lever 41, bears against the rear end of a lever 46. The lever 46 is pivotally mounted intermediate its ends on a pin 47, and the front end of the lever extends under a hook 48 on a dog 49 carried by the plunger 20. The dog 49 is pivotally mounted in a slot 50 in the center of the plunger (see Figs. 4, 5 and 6), on a pin 51, and the upper hooked end of the dog is pressed at all times in the direction of the lever 46 by a small spring 52 which is seated in a recess in the plunger. The dog is provided below the pin 51 with a projection 53 which acts against one side of the slot 50 in the plunger to limit the extent to which the dog can be tilted by the spring 52. The rear end of the lever 46 is maintained at all times in engagement with the roller 45 by a spring 54 which is positioned beneath that end of the lever. This spring also serves to maintain the operating lever 41 elevated, which is the normal position of that lever when the machine is not actually in operation.

When the plunger 20, in being raised by a downward movement of the handle 44, approaches its uppermost position, a beveled surface 55 on the top of the dog 49 will come into contact with a stud 56 in the top of the casing 16. As the plunger is elevated into its highest position this stud will cam the upper end of the dog forwardly, and as soon as the hook 48 on the dog clears the front end of the lever 46 the plunger will be released and will travel downwardly in the guideway 19 under the action of the then compressed spring 35.

The lower part of the front wall of the guideway 23 for the blade 21 consists of a removable plate 57. This plate is held in position by two thumb screws 58 which pass through apertures 59 in two side flanges 60 on the plate into threaded openings in the sides of the arm 15 (see Figs. 2 and 12). The apertures 59 are of keyhole shape and the shanks of the screws near the heads are of conical shape, whereby when the screws are loosened the plate 57 can be pulled away from the end of the arm 15 a short distance

without the screws having to be entirely removed and when the screws are tightened with the plate pushed back the latter will be drawn into exactly the right position by the centering action of the conical portions of the screws on the enlarged portions of the keyhole apertures. When the plate 57 is pushed back slots 61 in the ends of the flanges 60 will engage with indexing pins 62 on the arm 15, insuring proper vertical registration of the plate 57 with the upper fixed portion of the guideway 23. This construction gives easy access to the guideway 23 at the point where the staples enter the same, and insures an accurate positioning of the parts after the guideway has been cleared. 15

The front end of the head 11 is normally maintained in a slightly raised position with respect to the base 10 by means of a spring 63 (see Fig. 9) which is located between the head and the base in the bracket 13 at a point a little in front of the hinge connection 14. The spring 63 acts to support a bolt 64 which extends upwardly through an aperture in the base and is provided at its upper end with a nut 65. The nut 65 is prevented from turning by reason of its close fit with the sides of the bracket, and the spring 63 is compressed between the nut and the bottom of the bracket. When the machine is operated the initial pressure placed on the handle 44 will move the head 11 downwardly against the yielding resistance offered by the upwardly sprung-pressed bolt 64, forcing the head into engagement with the paper or other material on the base 10. To vary the normal spacing between the head and the base it is merely necessary to turn the bolt in one direction or the other.

When it becomes necessary to insert a fresh supply of staples into the guideway 26 in the arm 15, the finger piece 32 is unhooked from the stud 29 and is pulled out and hooked over a stud 66 on the rear end of the casing 16, as shown in dotted lines in Fig. 2. After this has been done the follower 28 can be backed out of the open rear end of the guideway 26 and the new supply of staples can be inserted into the guideway without either the draw band or the finger piece being in the way.

I claim:

1. In a stapling machine, a head containing in the front portion thereof vertically movable staple driving plunger, a spring in the rear portion of the head for moving the plunger downwardly to drive a staple, a power transmitting connection in the head between the spring and the plunger, an operating lever having a handle which when depressed raises the plunger against the yielding resistance of the spring, a releasable connection between the operating lever and the plunger which includes a pivoted hook on the plunger, and means for automatically moving the hook into a disengaged position when the plunger reaches the upper end of its movement. 50

2. In a stapling machine, a head containing a vertically movable staple driving plunger, a spring for moving the plunger downwardly to drive a staple, and means for transmitting the force of the spring to the plunger consisting of a driving lever which is pivoted intermediate its ends to the casing with its front end in engagement with the plunger and its rear end in engagement with the spring. 65

3. In a stapling machine, a head containing a vertically movable staple driving plunger, a spring for moving the plunger downwardly to drive a staple, means for transmitting the force of the 70

5. In a stapling machine, a head containing a vertical guideway, and a staple driving blade in the guideway, said guideway being characterized by a removable front wall section provided with side flanges, and screws passing through elongated keyhole apertures in the flanges into threaded openings in the sides of the head for securing the removable front wall section in operative position, said screws having enlarged shank portions which index in the enlarged ends 10 of the keyhole apertures when the screws are tightened with the front wall section in operative position. 5
10. 4. In a stapling machine, a head in the form of a hollow casing, a vertically movable staple driving plunger in the front of the casing, a coil spring in the rear of the casing for moving the plunger downwardly, a driving lever pivoted intermediate its ends to the casing with its front end in engagement with the plunger and its rear end in engagement with the spring, an operating lever pivoted at its rear end to the casing and provided at its front end with a handle, a hook 15 pivoted to the plunger, a lifting lever pivoted intermediate its ends to the casing with its front end in engagement with the hook and its rear end in engagement with the operating lever, and a stop in the casing above the hook for camming the latter out of engagement with the front end of the lifting lever when the plunger reaches its uppermost position, whereby to allow the plunger 20 to descend under the action of the spring. 10
15. 5. In a stapling machine, a head containing a vertical guideway, and a staple driving blade in the guideway, said guideway being characterized by a removable front wall section provided with side flanges, and screws passing through elongated keyhole apertures in the flanges into threaded openings in the sides of the head for securing the removable front wall section in operative position, said screws having enlarged shank portions which index in the enlarged ends 10 of the keyhole apertures when the screws are tightened with the front wall section in operative position. 5
20. 6. In a stapling machine, a casing, an underlying arm which is connected to the casing at its front end and is separated from the casing at its rear end by an intervening slot, a staple driving mechanism positioned in the casing, a staple follower slidably mounted on the arm in the slot, a tensioned draw band for the follower having a 25 finger piece detachably looped over a portion of the follower, and a hook on the rear end of the casing for holding the finger piece and draw band in an out-of-the-way position while the follower is being removed or replaced. 25

EDWARD KRANTZ.
